Howson & Howson.

UNITED STATES PATENT OFFICE.

WILLIAM HERBERT DERBYSHIRE, JR., OF CHAMBERSBURG, PENNSYLVANIA.

EXPANSION WEDGE.

Application filed October 11, 1921. Serial No. 506,985.

To all whom it may concern:

Be it known that I, WILLIAM H. DERBYSHIRE, Jr., a citizen of the United States, residing in Chambersburg, Pennsylvania, have 5 invented an Expansion Wedge, of which the following is a specification.

The object of this invention is to provide means for compensating uneven expansion or contraction in two associated elements of 10 a structure, the invention finding a particularly valuable application to drop hammers and similar machines comprising an anvil and an anvil cap detachably secured therein.

In machines of the type mentioned, it is 15 customary to make the anvil of cast steel and the cap of forged steel, and when during operation of the machine the parts become heated there is an unequal expansion tending to loosen the cap in the anvil, the latter 20 having the higher coefficient of expansion and expanding more rapidly under the effects of the heat. It is the practice to employ a wedge to secure the cap to the anvil, and this wedge during operation of the machine 25 is periodically driven in to retain the cap securely to its seat and to prevent its displacement on the anvil.

Also when operation of the machine is discontinued and the parts gradually cool, 30 the cast metal anvil contracts more rapidly than the forged cap, and unless the wedge is driven out or loosened to permit free contraction, there invariably results damage to one or the other of the parts due to the 35 severe stresses set up.

I have discovered that by associating with the parts of unequal coefficient of expansion, a body of material whose coefficient of expansion is higher than that of either of 40 the said parts, in such manner that in expanding it tends to tighten and in contraction to loosen the connection therebetween, I am able to maintain a tight connection between the parts regardless of the temperature changes, this being due to the fact 45 that the material of relatively high coefficient of expansion both expands and contracts more rapidly than either of the other parts. Regardless then of the unevenness 50 of the expansion, this body will maintain continuously a tight connection, and upon cooling of the parts and consequent contraction, the more rapid contraction of the material permits free expansion of the other

parts, and thereby eliminates possibility of 55 the destructive stresses.

In the attached drawings:

Figure 1, is a fragmentary perspective showing the upper cap containing portion of 60 an anvil;

Fig. 2, is a longitudinal section of a wedge 60 constituting an embodiment of my invention, and

Fig. 3, is a view in perspective of the wedge.

With reference to the drawings, 1 indicates a portion of the anvil of a drop hammer or similar machine, and 2 an anvil cap which is mounted in a recess 3 in the anvil, the sides 4 of the recess being beveled inwardly and the lower portion 5 of the cap being dovetailed, as clearly shown. The dovetailed portion 5 of the cap is somewhat narrower than the recess 3 in the anvil, and in the present instance a wedge 6 is inserted 75 in the space between the cap and the anvil to maintain a tight fit between these elements.

In the present instance I have illustrated the material of relatively high coefficient of 80 expansion applied in the form of inserts in the sides of the wedge 6, these inserts, indicated by the reference numerals 7, 7, being suitably secured in recesses in the sides of the wedge 6, as clearly shown in the drawings.

In practice, the wedge 6 is applied in a manner exactly similar to the wedge of the usual form, being driven in to form a tight fit between the anvil and the cap.

As the parts become heated during operation of 90 the machine, the inserts 7, which in the present case may be of copper, will tend to expand, and due to their relatively great

expansion will take up any looseness developing between the anvil and the cap due 95 to uneven expansion of these parts.

There will be found no necessity for adjusting the wedge to a new position to take up this developing looseness.

As the parts cool after operation of the machine ceases, all danger 100 from uneven contraction is eliminated due to the fact that the inserts contract more quickly than either the anvil or the cap and thereby give space for the contraction of the anvil.

It will be apparent that the invention in principle will find applications other than that herein set forth, and further that

numerous modifications in the method of application are possible with no departure from the essential features of the invention.

I claim:

5. 1. The combination with a pair of associated bodies having different coefficients of expansion, of an element constituting securing means between said members and having a coefficient of expansion higher than 10 that of either of said associated members.
2. The combination with a pair of associated members of different coefficients of expansion, one of said members having a recess occupied by the other, of an element inserted between the members for securing the one in the other and comprising a material having a coefficient of expansion higher than that of either of the members.
3. The combination with a pair of associated members of different coefficients of expansion, one of said members having a recess occupied by the other, of an element inserted between the members for securing the one in the other and comprising a body 25 having inserted in the face thereof a material of higher coefficient of expansion than that of either of said members.
4. The combination with an anvil, of an

anvil cap, and means for securing the cap to the anvil including a wedge inserted 30 therebetween, said wedge comprising a material having a coefficient of expansion higher than that of either of the anvil or cap.

5. The combination with an anvil having 35 a recess, of an anvil cap adapted to fit within the recess, and means for securing the cap in the recess comprising a member inserted between the anvil and the cap and comprising a material having a coefficient 40 of expansion higher than that of either the said anvil or cap.

6. The method of compensating for unequal expansion and contraction in two bodies, one of which is confined within a recess in the other, which consists in inserting 45 between the bodies an element having a coefficient of expansion higher than either.

7. The combination with a pair of members subject to different degrees of expansion and contraction, one of which members is confined within a recess in the other, of a securing element inserted between the members and having a coefficient of expansion exceeding that of either.

WM. HERBERT DERBYSHIRE, JR.
